UNITED STATES PATENT OFFICE.

HANSON ROBINSON, OF SOUTH BEND, INDIANA.

FLUSHING-NOZZLE.

1,033,195.

Specification of Letters Patent. Patented July 23, 1912.

Application filed September 29, 1911. Serial No. 651,906.

To all whom it may concern:

Be it known that I, HANSON ROBINSON, a citizen of the United States, residing at South Bend, in the county of St. Joseph 5 and State of Indiana, have invented certain new and useful Improvements in Flushing-Nozzles, of which the following is a specification.

This invention relates to improvements in 10 flushing nozzles of the type used on flushing wagons which are mainly employed for washing city pavements, and has for its particular object to provide a device of this character that will discharge a flat broad 15 stream at an angle to the pavement and means for causing said stream to contact with the pavement with equal force throughout its flushing area.

A further object is to provide a nozzle 20 formed of separate sections, whereby its interior can be polished to make its discharge more effective.

With the above and other objects in view, the present invention consists in the combination and arrangement of the parts as will 25 be hereinafter more fully described, shown in the accompanying drawing, and pointed out in the appended claims, it being understood that changes in the form, proportion, 30 size and minor details may be made within the scope of the claims without departing from the spirit or sacrificing any of the advantages of the invention.

In the accompanying drawing:—Figure 35 1 is a perspective view of my improved device. Fig. 2 is a front elevation thereof, and Fig. 3 is a sectional view taken on the line 3—3 of Fig. 2.

Like numerals of reference designate corresponding parts in all of the figures of the 40 drawing.

Nozzles of this character are especially applicable to flushing wagons provided with a water tank and a tank of compressed air, 45 by means of which the water is discharged with greater or less force, and they are designed to project a diverging stream against the pavement at an inclination to wash the debris toward the gutters, but in nozzles of 50 this character heretofore used, the force of the stream at the point of its greatest throw is usually somewhat less than its nearest throw. This is caused by the resistance of the air which tends to break the flat stream 55 into a spray, and as the flushing value of the nozzle depends upon keeping the stream

solid until it strikes the surface of the street, it caused the present improvement to be devised.

Referring to the drawing, 4 and 5 designate the two sections of the improved nozzle, each of which is provided with inclined and rounded walls having diverging sides with flanges 6, which when brought into register with each other, form a tapering 60 chamber 7 which gradually merges into a flat wide mouth 11 in a front wall 8 formed by relatively thick flanges on the widest part of each section. The sections are also formed with semi-cylindrical extensions 9 at their inner ends so that when brought together a cylindrical neck or nipple is formed by which the nozzle is secured to the discharge pipe 10 of the flushing cart or wagon in any well known manner. The 70 front walls of the sections are recessed on their dividing lines to form a wide narrow discharge opening 11, and said recesses are gradually deepened toward one side to form said discharge opening of gradually increasing depth from one side to the other. Thus when the device is in operation a flattened stream of increasing volume in cross section is discharged therefrom, which preserves its solidity throughout its 80 flushing area. In other words, the water strikes the pavement with equal force for the entire width of the stream. The sections are secured together preferably with screws 12, and it will be understood that if 90 desired suitable packing may be inserted between the sections to prevent leaking. Previous to securing the sections together the walls of the chamber 7 are highly polished, which renders the delivery of the water 95 more effective. Thus the advantage of forming the nozzle in sections can be clearly seen.

Nozzles of this type are usually positioned to discharge the stream from a point near 100 the wagon to a distance from the wagon, and by forming the discharge mouth of gradually increasing width from one side to the other, the widest portion of the mouth being adapted to throw the water the 105 greatest distance, the volume of water discharged will retain its solidity or force throughout.

Having thus described the invention, what 110 is claimed is:—

1. A flushing nozzle formed in sections, each of which comprises a rounded and in-

clined wall having diverging sides and terminating at its forward end in a thickened flange which is provided with a recess on one of its faces, said recess increasing in depth from one side to the other, and side flanges provided with apertures, whereby said sections can be secured together to form a tapering chamber merging into a flat wide mouth of increasing depth from one side to the other.

2. A flushing nozzle formed in sections,

each of which comprises a rounded, inclined wall having diverging flanged sides and recessed at its front edge, said recess increasing in depth from one side to the other.

In testimony whereof I affix my signature in presence of two witnesses.

HANSON ROBINSON.
